SPARK PLUG

Carl E. Berstler, Reading, Pa.

Application October 12, 1940, Serial No. 360,869

6 Claims. (Cl. 123—169)

My invention relates to spark plugs, and particularly to novel means providing more effective sealing and operation thereof.

In spark plugs of internal combustion engines, electrical conductors must extend, through openings in the walls of the engine heads, into the combustion chambers, and be thoroughly insulated from the metal, and not occupy undue space.

As a consequence, the plugs and insulators are small, and it is difficult to extend the conductors through the insulators, to prevent leakage of the highly compressed gas along the conductors, and to maintain the plugs of simple construction and low cost.

Such leakage causes various adverse effects according to its extent, ranging from only slightly decreased engine efficiency to total inoperativeness and destruction of the plugs.

In the more recent greatly increased combustion chamber pressures of automobile and other vehicle engines, the subject of spark plug leakage, through the insulators along the inner electrodes, has become of added importance, whereby to avoid unexpected failures, causing annoyance and delay in ordinary operation, and more costly results in service of greater importance.

The outer ends of former plugs, in standard practice, have been of simple obvious construction, not especially taking into consideration beyond ordinary expediency the masses, shapes and relations of the conducting and non-conducting elements, not being guarded sufficiently against gas leakage, deterioration and injury, and not being especially adapted for form and setting, or for temperature and electric control.

Also, the factor of fouling of the plugs at the firing ends, which has always been a difficult problem, has become increasingly so from the greater danger of the above-mentioned leakage in modern practice.

The inner ends of spark plugs have been the subject of probably hundreds of experiments, and very minor physical changes of the shapes, volumes or masses, and relations of metal, insulating material and free space, sometimes cause variations of operation greatly out of proportion to the apparent extent of such changes.

Further, plugs of one make, size and type may be required to operate in any of various classes of work, represented by pleasure cars, light and heavy trucks, tractors, motor boats, and the like, and each of these subject to varying degrees of light or heavy, and continuous or intermittent operation, under all kinds of weather, temperature, load and other conditions.

Fouling occurs from various reasons, such as poor mixtures of gas and air, oil in the combustion chambers, cold starting, incomplete combustion, and other effects, so that, in designing a plug, all of these factors must be considered.

Plugs of standard and well known makes have tubular inner-end shell portions through, or into, which extend the inner electrodes, and the inner end portions or tips of the insulators, the combined masses of the insulator and electrode materials occupying most of the space in the inner-end shell portions.

These shell portions, the inner ends of which are open, form dead-air spaces or pockets about the insulators, which, because of the above-mentioned space occupancy of the insulator and electrode masses in the inner end of the shell, lack of fluid circulation through the shell walls, or for other reason, apparently do not receive the fire or heat of combustion to sufficient extent to maintain the insulators clean, and do not contain good mixtures for fast burning.

It is among the objects of my invention to overcome all of the above-mentioned objections, and to provide a spark plug that shall not only be more effective, but that shall remain effective over a greater period of time.

Another object of the invention is to so seal a spark plug as to prevent leakage through the insulator along the inner electrode, and to effect such sealing whereby to render it lasting, and free from undue complication and expense.

Another object of the invention is to improve the form, protection, durability and operation of a spark plug at its outer end.

Another object of the invention is to provide a novel spark plug inner-end structure whereby to improve the operation of an engine, to prevent fouling of the plug, and to render the outer end more effective.

Another object of the invention is to improve both ends of a spark plug, each in relation to the other, as in sealing the plug at its outer end to prevent fouling at the inner end, and to improve the circulation and combustion of gas at the inner end whereby to render the outer end more durable, and the plug and the engine more efficient, without changing the engine parts.

Another object of the invention is to provide a spark plug with a seal having a path, along which gas tends to escape, that shall be tortuous, locally blocked by pressure concentrating elements, and augmented by hardened fluid sealing material in a manner effectively preventing such escape.

Another object of the invention is to provide the

aforementioned seal at the outer end of the plug in a manner also favorably affecting the temperature and electric control, and having improved form or setting.

Another object of the invention is to provide such outer-end seal whereby it may advantageously be adapted to plug insulators of standard forms, or to insulators of special forms.

Another object of the invention is to provide better circulation of gas or fire about the exposed inner end of the insulator of a spark plug by means of either or both the feature of enlarging the free space between an inner end length of the shell and the insulator, and the feature of providing passageway means through and along the exterior of the side wall of the inner shell length.

Another object of the invention is to provide a spark-plug seal, and its method of assembly, whereby to facilitate the effectuating of strong mechanical pressure between the seal parts, without undue friction, or the requirement for the application of undue force, and to prepare certain of the parts subject to such pressure to avoid disruption thereof.

A further object of the invention is to provide a spark plug that shall be simple and durable in construction, economical to manufacture, and effective in its operation.

With such objects in view, as well as other advantages which may be incident to a utilization of the improvements, the invention comprises the elements and combinations thereof hereinafter set forth in the specification, drawing and claims, with the understanding that the several necessary elements constituting the same may be varied in proportion, arrangement and texture, without departing from the nature and scope of the invention.

In order to make the invention more clearly understood, means are shown in the accompanying drawing for carrying the same into practical effect, without limiting the improvements, in the useful applications thereof, to the particular constructions, assemblies and operations which, for the purpose of explanation, are made the subject of illustration.

In the drawing:

Figure 1 is an enlarged view, partially in side elevation, and partially in vertical central-plane section, of a spark plug constructed in accordance with the invention;

Fig. 2 is a bottom plan view of the structure of Fig. 1;

Fig. 3 is an elevational view, taken at right angles to Fig. 1, from the left thereof, of the lower portion of the plug;

Fig. 4 is a view on a scale reduced from that of Fig. 1, partially in side elevation and partially in section, of an insulator, an inner electrode, and outer-end seal and terminal parts of a spark plug constituting a modification of the invention; and

Figs. 5 to 11, inclusive, are views, similar to the top portions of Fig. 1, of the invention thereof in further modified forms.

In practicing the invention, a fluid-impervious cap-like structure, as of an imperforate dome-like metal element, is disposed over the outer ends of both the insulator and inner electrode means of a plug, with gasket sealing means compressed between the insulator and the cap structure, and terminal means cooperating with the electrode means through the cap structure.

In an effective form of the invention, hardened

fluid sealing material desirably augments the gasket seal on the cap, insulator and gasket parts in or about the latter. Either the cap or the outer insulator end may have the form of a cup surrounding the gasket means, or fitted over a projection on the other, and pressing the gasket means.

In each of several effective forms of the invention, the porcelain has, or is provided with, an outer-end gasket seat, whereby the latter surrounds, or is surrounded by, a portion of the insulator material.

Correspondingly, in any of the latter forms, the fluid-impervious cap may telescope the insulator means radially inwardly or outwardly thereof, or both, whereby to form a tortuous path against the escape of gas.

The cap, although desirably of one metal piece having a distributor cord terminal connector portion, more effectively of the snap-fastener, or quick-detachable type, is in any event, adapted to have the terminal cooperate with the electrode through the imperforate, or fluid-impervious, portions thereof.

To avoid irregularities or inequalities of pressure, as occurs between cooperating broad-area gasket pressure faces, caused by discrepancies in the uniformity of the faces, to reduce friction between such faces in effecting the seal, and to avoid disruption of parts, certain parts on the insulator may advantageously be baked before, and other parts baked after assembly, and the gasket seat and gasket arranged such as to reduce friction therebetween, and to receive local or concentrated pressure within the outer lateral limits of the structure surrounded by a portion of the insulator or the cap.

In an effective form, gasket means is placed between the insulator and a terminal element 40 rotatively or screw threadably mounted on an electrode secured to the insulator. One portion of the insulator and terminal cooperates with the gasket means to prevent turning of the latter, and another portion cooperates with the gasket means 45 for reduced friction contact therewith.

Such outer-end structure increases the efficiency, and reduces fouling, of the inner end of the plug irrespective of the particular construction of the latter, but more effectively in combination with the form or forms of the present invention, whereby the inner-end length of the shell either or both has a perforate side wall cooperating with passageway means along the outer side of such wall to the inner end of the shell for communication with the combustion chamber of an engine, and cooperates with the insulator and inner electrode means to provide more free space along the inside of such inner-end shell length.

The latter feature alone, or with the outer-end plug structure hereof, eliminates the dead-air space heretofore in the inner end of the shell, provides circulation of the gas and fire of combustion all about the inwardly exposed insulator surface in the inner end of the shell, thereby maintaining such surface clean, or rendering it self cleaning, and adds its volume or circumscribed space to that of the combustion chamber proper, with the result of better circulation and faster burning in the thus enlarged combustion chamber as a whole, greater power, better pick up, and easier starting of the engine, and longer maintenance of these qualities.

Referring to the drawing, as better seen in Fig. 1, a spark plug constructed in accordance

with one form of the invention comprises, in general, dielectric or insulating means D, inner electrode means E, outer-end terminal means T, a shell S having an inner-end combustion chamber portion C, and ground electrode means G on the shell portion C.

The insulator means D, although it may be constructed of various numbers and kinds of materials, and parts, is shown, in this instance, of one homogeneously integral piece, known as a porcelain, having an outer-end length 17 protruding from the shell S, a body 18, and a lower-end length or tip element 19. The body 18 is of greater diameter than the outer and inner-end lengths 17 and 19, respectively, to provide upper and lower shoulders on the body constituting seats for sealing gaskets 22 and 23, respectively, disposed between the insulator D and the shell S.

The insulator has an opening extending entirely therethrough around the central longitudinal axis of the plug, this opening having a smooth cylindrical surface about the lower length of the electrode E, and a screw threaded upper length of larger diameter for cooperation with a screw threaded portion 24 of the electrode E.

The upper-end length 17 of the insulator means D has, in the form of Fig. 1, a flat-plane transverse end surface or shoulder at right angles to the electrode means, in which shoulder is provided an annular groove or channel for the reception of a gasket 27.

The electrode means E further comprises a screw threaded top-end length 28, an arcing lower-end length 29, and a disk-like portion 30 forming a part of the electrode, or sealed thereto, and extending laterally therefrom over the outer-end surface or shoulder having the above-mentioned groove for the gasket 27.

In such instance therefore, the gasket both surrounds, and is surrounded by, portions of the insulator D forming the groove for the gasket, and is radially spaced inwardly from the outer limits of the insulator, and outwardly from the outer limits of the portion 30.

The outer-end terminal means T, shown in this instance as of one homogeneously integral piece of metal, such as brass, which may be lacquered, or chromium or nickel plated, has a cap-like portion 32 of substantially dome-shape, and a portion 33 for substantially snap-fastener reception of a cooperating portion on a distributor cord or conductor.

The means T, being thus imperforate and substantially impervious to the passage of gas therethrough, is further provided with a tapped hole for mounting it on the screw threaded electrode portion 28, and a depending outer perimetral bottom flange 34 surrounding the gasket 27, and the portion 30 of the electrode means E. The cap or dome portion 32, in this instance, is thus of inverted substantially cup-shape, having a countersunk lower face surrounded by the flange 34 for pressure against the gasket 27, and which may also be provided with a supplemental groove for seating over, and about and within, the gasket similar to the manner in which the insulator groove seats under, about and within the gasket.

In assembling the parts, a hardening fluid sealing material, such as cement, is placed all along the length of the electrode E in the insulator D, over and under the gasket 27 and the portion 30, between the gasket and the flange 34, under the latter, and between the gasket and the portion 30. Such parts may be baked to set the cement and anchor the electrode before mounting the

terminal T, or all parts cemented together and subsequently baked.

When the terminal T and the insulator D are advanced toward each other, by action of the terminal T on the screw threaded top end length 28 of the electrode, and of the insulator on the screw threaded portion 24 of the electrode, the gasket is locally compressed, as above indicated, and the cement forced strongly against all adjacent surfaces, and into all adjacent crevices, thereby very greatly increasing the resistance to the leakage of fluid through the plug along the electrode under the violent urge of the compressed and exploded gases from the combustion chamber, over the resistance offered by the plugs of prior practice.

Although shown as in a groove in the insulator, against a flat face of the terminal T, this relation may be reversed, whereby the gasket engages a large surface in the groove to hold the gasket against turning, and the flat face, which initially has only line contact, and never very great surface contact, with the gasket, thus reduces the friction of the contact compared to that between broad area surfaces, as above mentioned.

The terminal means T, having a metallic exposed surface of substantially continuous laterally outward and longitudinally inward slope, or convex curvature, from the outer-end portion 33 thereon to the line of meeting of the flange 34 with the insulator D, and constituting substantially an uninterrupted extension of the insulator length 17, has remarkably effective form or setting. Having substantial metallic body and surface area, the means T also contributes to cooling the plug, and more widely and uniformly spreads the electric field than do the usual smaller metal top parts of ordinary plugs.

The shell S has a top flange 31 pressed inwardly and downwardly over the gasket 22, a tapered lower inner body seat against which the gasket 23 and the insulator body 18 are forced by the flange 31, and a bottom shoulder 38 for seating on a gasket on an engine head into an opening of which the inner-end shell portion C extends.

The portion C, see Figs. 1, 2 and 3, has, in this instance, aperture means through its longitudinal side wall, in the form of three holes 42 near the shoulder 38 equally spaced about the plug. Grooves 43, which conceivably, in certain instances, might be provided in the engine head, are however believed generally more effectively provided in the shell, as shown, each extending from one of the holes 42, and cutting through, or traversing, screw threads 44 on the portion C to the inner end of the latter, for communication with the combustion chamber of the engine.

By this construction, in which the number, form and relation of the holes and grooves may be varied, the exposed surface of the insulator tip 19, is subject to the fire of combustion, whereby to maintain the plug clean at this tip, or to render it self cleaning, if fouled before use with the invention.

As shown, the tip 19 extends only a short distance into the shell portion C, thereby providing free space of substantial volume relative to the mass of the insulator and electrode means along the portion C for better circulation of gas and the fire of combustion. This tip may be of other shape and diameter, and extend a greater or less distance toward the ground electrode G to any selected point in a manner consistent with the above-mentioned circulation, and it is con-

templated that the additional free space thereby provided may be utilized alone, or in combination with the holes 42 and the grooves 43, or equivalent means.

The free space within the shell portion C, around the insulator tip 19, which heretofore acted as a dead air space, and in many cases readily became literally choked with carbon, becomes, by the invention, entirely free from such fouling.

In the form of Fig. 1, the compression of the gasket 27 reacts between the terminal T and the threaded portion 24 of the inner electrode E, through the upper part of the insulator.

In the modified form of Fig. 4, a terminal structure T, the same as above set forth, reacts with an inner electrode 47, through a greater length of an insulator 48 to compress the gasket 27, in the same manner as in the first form, by reason of an enlargement 49, either fixed to, or constituting an integral part of, the electrode 47, which enlargement has a tapered or beveled top seat engaging a corresponding seat at the top of an enlarged lower portion 52 of the opening in the insulator through which the electrode extends. This insulator and electrode are free from the screw threads at the upper part of the insulator of Fig. 1, as well as of the disk-like portion 30 over the top of the insulator.

As shown in the form of Fig. 5, a terminal Ta telescopes radially and longitudinally inwardly of an insulator Da, through a series of steps forming seats for gaskets 53 instead of the single gasket 27, the terminal being free from the bottom flange 34, although such flange may be provided, and cooperating with a longer upper screw thread portion on an inner electrode Ea.

In the form of Fig. 6, a terminal Tb has a separable snap fastener portion 57, as may any of the forms, instead of the integral portion 33 of Fig. 1. The terminal Tb also has depending lower portions 58 telescoping longitudinally inwardly, and radially and outwardly, of portions of an insulator Db, in which gaskets 59, corresponding to the gaskets 53 of Fig. 5, are similarly compressed, and form a different tortuous path against gas leakage.

An inner electrode Eb has a shorter upper screw thread portion corresponding to the portion 28 of Fig. 1, and is disposed substantially entirely within the insulator Db.

In the form of Fig. 7, the structure is similar to the form of Fig. 1, in having like insulator means D, electrode means E, screw threaded portions 24 and 28, a portion 30, and a gasket 27, but a terminal Tc is additionally provided with a flange 64, rounded for electrostatic, and other purposes, and telescoping the upper end of the insulator D, whereby to surround the gasket 27, and to provide additional sealing.

In Fig. 8, an insulator Dd has a sloping top end seat for a similarly sloping gasket 67, and an inner electrode E having the screw thread portions 24 and 28, the disk-like portion. A terminal Td has a sloping seat for engagement with the gasket 67, and a depending flange 68, similar to the flange 34 of Fig. 1, disposed over a flat annular top surface portion on the insulator around the sloping gasket seat thereof.

In Fig. 9, the structure is similar to that of Fig. 8, including an electrode E having the screw thread portions 24 and 28, and the disk portion 30. Seats on an insulator De and a terminal Te, although sloping, as in the device of Fig. 8,

are rounded to compress a gasket 69 therebetween. In this form, the top end of the insulator De is similar to the top ends of insulators heretofore employed, with the exception of a shoulder 72, removal of which would leave the device still operative, thus illustrating how the invention may be applied to such former insulators. In the latter case, however, the lower end of the terminal Tc could be modified to give better symmetry.

As shown in Fig. 10, the structure is similar to that of Fig. 6, with the outer portion 58 of the latter removed, and an insulator Df not having a seat for a gasket under the flange. An electrode Ef likewise does not project from the top of the insulator, and a terminal Tf compresses gaskets 73 against the insulator, the inner gasket being disposed over a disk-like portion 71 similar to the portion 30 of Fig. 1. Further, surfaces 14 on the terminal Tf, such as the side surfaces of a nut, or flat areas on a cylinder, may be provided in any of the forms, or holes or slots, or other means substituted therefor to cooperate with a wrench or the like in mounting the terminal in position.

In Fig. 11, a terminal Tg is similar to the terminal Tb of Fig. 6, with the inner portion 58 of the latter removed, but having a relatively heavy outer depending flange 82 telescoping a top end cylindrical projection on an insulator Dg, and bearing against gaskets 83 on the insulator. The insulator Dg also has a flange or bead, illustrating one of several forms of such bead or contour which may be provided on any of the insulators hereof for electrostatic, ornamentation, gasket seating or other reasons.

In each of the forms of Figs. 4 to 11, inclusive, the hardening fluid sealing material may be applied as set forth above.

40 The number of forms shown is not an attempt to set forth all, but only within reasonable illustration, of elements which may be produced within the purview of the actual invention.

I claim as my invention:

45 1. A spark plug comprising electrode means, insulator means surrounding said electrode means, and a shell surrounding the insulator means including a tube-like inner end length having fluid passageway means laterally therethrough and means providing for the passage of fluid between said passageway means and the inner end of said tube along a substantial length of the latter closed to the interior thereof.

50 2. A spark plug comprising electrode means, insulator means surrounding said electrode means, and a shell surrounding the insulator means including a tube-like inner end length having fluid passageway means laterally therethrough and groove means of substantially channel section extending along the exterior of the tube from said passageway means to the inner end of the tube.

55 3. A spark plug comprising electrode means, insulator means surrounding said electrode means, and a shell surrounding the insulator means including a portion sealed relative to the insulator means and a tubular-wall inner end length having fluid passageway means laterally therethrough closely adjacent to said sealed portion and means providing for the passage of fluid along a length of said tubular wall closed to the interior of the tube between said passageway means and the inner end of the tube.

60 4. A spark plug comprising electrode means, insulator means surrounding said electrode

means, and a shell surrounding the insulator means including a portion sealed relative to the insulator means and an exteriorly screw threaded tube-like inner end length having aperture means laterally therethrough closely adjacent to said sealed portion and means intersecting the screw threads providing for the passage of fluid along a length of said tube closed to the interior of the tube between said aperture means and the inner end of the tube.

5. A spark plug comprising electrode means, insulator means surrounding said electrode means, and a shell surrounding the insulator means including a portion sealed relative to the insulator means and a tubular-wall inner-end length having fluid passageway means laterally

therethrough closely adjacent to said sealed portion and groove means of substantially channel section providing for the passage of fluid between said passageway means and the inner end of 5 said tubular wall.

6. A spark plug comprising electrode means, insulator means surrounding said electrode means, and a shell surrounding the insulator means including a tube-like inner end length for 10 insertion into an engine block, said tube having fluid duct means laterally therethrough and means whereby the tube and the block form passageway means along the outside of the tube communicating with said duct means.
